[57] CLAIM

The ornamental design for a toy ship, as shown and described.

DESCRIPTION

FIG. 1 is a perspective view showing the left side of the toy ship showing my new design;

FIG. 2 is a top plan view of the ship of FIG. 1.

FIG. 3 is a side elevational view of the right side of the

FIG. 4 is a left end elevational view thereof; and

FIG. 5 is a bottom plan view thereof.
